(57) **CLAIM**

The ornamental design for propeller, as shown and described.

DESCRIPTION

FIG. 1 is a rear perspective view of a propeller showing my new design;

FIG. 2 is a front perspective view thereof;

FIG. 3 is a rear view thereof;

FIG. 4 is a front view thereof;

FIG. 5 is a left side view thereof;

FIG. 6 is a right side view thereof;

FIG. 7 is a bottom view thereof; and,

FIG. 8 is a top view thereof.

The structural features depicted by broken lines, in FIGS. 3 and 4, have been shown for the purpose of illustrating portions of the propeller that form no part of the claimed design.

1 Claim, 4 Drawing Sheets

FIG. 3

FIG. 4

FIG. 5**FIG. 6**

FIG. 7

FIG. 8
